FORCE-LASTED STITCHDOWN SHOE

Louis Sillman, Coytesville, and Hans Hacker, Rutherford, N. J., assignors to Flexline Shoe Company, a corporation of New Jersey

Application October 5, 1955, Serial No. 533,665

2 Claims. (Cl. 36—16)

The present invention relates to making shoes particularly ladies' shoes of the type customarily referred to as walking shoes. As the invention is especially applicable to the manufacture of ladies' walking shoes having open toes and backs, it will be described with references to shoes of that type.

It is an object of the present invention to make a shoe which is flexible and lightweight and is yet of sturdy, long wearing construction. A further object of the invention is to produce serviceable and comfortable walking shoes that fit the foot snugly and have a neat light-looking appearance. The invention further provides an improved method of manufacture whereby quality shoes can be produced at a lower cost.

The nature, objects and advantages of the invention will be more fully understood from the following description and claims in conjunction with the accompanying drawings which illustrate a preferred embodiment. In the drawings:

Fig. 1 is a perspective view of an upper of a shoe embodying the invention.

Fig. 2 is a fragmentary section taken approximately on the line 2—2 in Fig. 1.

Fig. 3 is a perspective view of a preassembled insole-outsole unit.

Fig. 4 is a perspective view illustrating one step of attaching the upper to the sole unit.

Fig. 5 is a perspective view illustrating a further step, the partially completed shoe being shown on a last and inverted.

Fig. 6 is a side view of a completed shoe.

Figs. 7 and 8 are cross sections taken respectively on lines 7—7 and 8—8 in Fig. 6.

As illustrated in Fig. 3, an insole 1 and outsole 2 are preassembled by adhesively uniting them at their toe portions only. The insole 1 has a ball portion 3 formed of a cushion material for example, a cork composition and a shank portion 4 and a heel portion 5 formed integrally of a bendable, yet firm and relatively hard material for example, fiber board or leather. The shank and ball portions are adhesively joined in a V-type dove tail 6 so that the entire insole is essentially of integral construction. Edges of the shank and heel portions of the insole are finished with a stitched-on binding 7. The outsole 2 is formed of flexible, firm wear-resisting material for example, leather or a plastic or rubber composition and comprises a ball portion 8, shank portion 9 and a tongue-like heel portion 10 of reduced width. The insole and outsole are united only at the toe and forward portion of the ball, the rear ball portions and shank portions being left free. The ball portion of the outsole is larger than that of the insole and projects beyond the edges of the insole approximately $\frac{1}{4}$ to $\frac{3}{8}$ inch. The shank portions of the insole and outsole are approximately the same width. A cover 11 of "upper" material, for example leather, fabric or plastic, overlies the toe portion of the insole and the forwardly projecting toe portion of the outsole.

2

An upper 13 (Fig. 1) is fabricated from suitable "upper" material for example leather, fabric or plastic accurately cut to pattern and comprises a vamp portion 14 and quarter portions 15. The upper is shown as being fabricated from two main pieces of material joined by a strip 17. A heel strap 18 attached to the rear of one of the pieces is received by a buckle 19 mounted on the upper rear portion of the other piece. Edges of the upper that are exposed in the completed shoe are suitably finished, for example by stitched binding 20. The upper preferably has a lining 21 (Fig. 7) and heel lining 22 (Fig. 4) formed of fabric, light leather or other suitable material. The quarter portions of the upper are cut to provide a lasting allowance 23 (see also Figs. 5 and 8). The vamp portion 14, on the contrary, has no lasting allowance, opposite side edges 24 being cut accurately to pattern so that in the completed shoe (Fig. 7) they abut the upper face of the outsole 2 without being turned outwardly or lasted inwardly.

The upper further comprises mudguard strips 25 (Figs. 1 and 2) secured to the opposite side edge portions of the vamp 14. The mudguard strips 25 extend from the open toe 26 to the junction of the vamp 14 with quarter portions 15 and are accurately cut from suitable "upper" material, being substantially straight and of uniform width except for tapered rear end portions 27. The strips 25 overly side edge portions of the vamp 14 and are securely united with the vamp, for example by adhesive and by stitching 28. The outer edges 29 of the mudguard strips 25 project approximately $\frac{1}{4}$ inch beyond the lateral edges 24 of the vamp, it being understood that this distance may vary by perhaps $\frac{1}{8}$ inch according to the particular style and size of the shoe being made. In cutting the mudguard strips 25, a slit 30 is formed approximately $\frac{1}{2}$ inch from the rear end of the strip and extends inwardly from the outer edge 29 to approximately the respective lateral edge 24 of the vamp. The mudguard strips 25 are unlined.

The upper 13 including the attached mudguard strips 25 as illustrated in Fig. 1, is next assembled with the insole-outsole unit shown in Fig. 3. To facilitate assembly of the upper and sole units, the inner faces of the projecting mudguard strips 25 and the upper surfaces of the projecting outsole portions are coated with adhesive to make them tacky. The projecting portions of the guard strips forward of the slits 30 are bent outwardly and pressed into place along the outwardly projecting edge portions of the sole so as to hold the upper temporarily in place on the sole unit as illustrated in Fig. 4. The sole is provided with nicks to indicate where to place the upper. The vamp portion of the upper is then permanently attached to the ball portion of the sole by stitching 32 which passes through the outsole and the cuttured edge portions of the mudguard strips 25 and extends from one of the slits 30 forwardly, across the toe and then rearwardly to the other of the slits 30. The slits 30 are thus defined in the beginning and ending of the stitching and facilitate the stitching operation. It will be noted that at the toe of the shoe, the stitching 32 passes through the forward portion of the material 11 covering the toe portions of the insole and outsole, thereby further securing the covering material. As the edges of the vamp portion 14 and lining 21 are not turned outwardly and stitched to the outsole with the guard strip 25, the edge of the sole and the finished shoe has a lighter, neater appearance and no moisture can soak in through the lining since the edge of the lining is not exposed. Moreover, since the vamp portion of the upper is not lasted, the ball portions of the outsole and insole are not separated by lasting allowances of the upper but come directly together to provide a smooth, flat, lightweight and flexible construction. However, the edges 24 of the

vamp are not exposed but are held between the guard strips 25 and the edges of the insole 1. The insole is sufficiently thick, for example $\frac{1}{8}$ inch, to form with the mudguard strips a recess to receive the edges of the vamp. The inside of the upper as well as the sole thus presents a smooth surface which contributes to the wearer's comfort.

The upper and sole unit are assembled and stitched together as illustrated in Fig. 4 without lasting. A last L is then inserted in the partially completed shoe and the shank portion of the insole is temporarily tacked to the last. The lasting allowances 23 of the quarter portions of the upper are then cement-lasting over the shank portion of the insole (Fig. 5) the shank portion 9 of the outsole being bent up out of the way so that it does not interfere with the lasting operation. The lasting of the instep portion of the upper makes it possible to shape the shoe accurately to the last and obtain a much better fit than is possible with conventional stitched-down shoes. In stitched-down shoes, it is difficult to obtain proper fit and prevent bulging of the upper particularly in the shank portion of the shoe. This difficulty is overcome by the method in accordance with the invention since the lasting of the quarter portion assures accurate molding of the upper. Moreover, by eliminating in the shank portion of the shoe, the laterally projecting sole and out-turned edges of the upper that are typical of stitched-down construction, it is possible to reduce the width of the shank and give it a trim, smart appearance. As seen in Fig. 8, the shank portions of the insole and outsole are of substantially the same width. Although the lasting allowance 23 of the quarter portion of the upper is interposed between the insole and outsole, the material is of single thickness and does not objectionably thicken the shank portion of the shoe.

In the operation of lasting, the quarter portions of the upper, the rear end portions 27 of the mudguard strips 25 are brought in over the insole so that they point inwardly toward one another in a direction transverse to the length of the shoe, and approximately perpendicular to the edges of the sole. The rear end portions of the guard strips are secured in place, preferably by adhesive and are securely held between the insole and the outsole. The bringing of the rear end portions of the mudguard strips in toward one another at rear of the ball portion of the shoe as shown and described, further assists in shaping the upper in the important transition zone where the quarter portion merges into the vamp. It further assists in giving the shoe a neat and streamlined appearance and increases its strength and durability. The slits 30 in the mudguard strips provide a safe transition from one type of construction to the other, avoiding the possibility of strain and breakage.

The inturned rear end portions 27 of the mudguard strips 25 and the lasted edge portions 23 of the upper are then roughened, a steel or other shank reinforcing the strip 33 (Fig. 8) is placed between the shank portions of the insole and outsole and the rear ball and shank portions of the outsole is cemented down using a press. If a wedge heel is to be used, no reinforcing shank is required. The shoe is preferably left on the last 2 or 3 days to become molded to the last. A heel 34 (Fig. 6) is then affixed to the heel portions of the insole and outsole, the tongue-like portion 19 of the outsole being received in a recess in the heel. Sponge rubber padding 35 (Fig. 8) is positioned to cover the heel and shank portions of the insole and a sock lining 36 is cemented in place.

The shoes made in accordance with the invention have a dressy appearance and yet are extremely serviceable and comfortable to wear. They thus help to resolve the dilemma with which women have long been faced as to wear shoes that are comfortable or shoes that are stylish.

While a preferred embodiment of the invention has been shown and described, it will be appreciated by those

skilled in the art that the method and construction in accordance with the invention can be used to produce a considerable variety of shoes. The invention is thus not limited to the particular embodiment shown by way of example in the drawing.

What we claim and desire to secure by Letters Patent is:

1. A shoe comprising an upper having vamp and quarter portions, said quarter portions only having lasting allowances, mudguard strips secured to opposite side edges of said vamp portion and projecting approximately one quarter inch beyond the edges of the vamp, said strips extending from the toe to the junction of said vamp and quarter portions and provided with a slit a short distance forwardly of the rear end of each of said strips, said slits extending inwardly from the edges of said strips to the edges of said vamp portion, an outsole having forepart and shank portions, an insole having forepart, shank and heel portions, the forepart of the insole affixed directly to the forepart only of the outsole, the lateral edges of the forepart of the outsole projecting outwardly beyond the edges of the insole, said mudguard strips having lower edge portions extending from the toe rearwardly to said slits turned outwardly and stitched to the projecting edge portions of said outsole, the side edges of said vamp portion abutting the upper face of the outsole and held between the mudguard strips and the side edges of the insole, the portions of said strips rearwardly of said slits and the lasting allowances of said quarter portions turned inwardly and secured between the shank portions of the insole and outsole to shape the shank portion of the shoe smoothly to the contour of the shank of a selected last, the rear ends of said mudguard strips pointing inwardly toward one another in a direction transverse to the length of the shoe.
2. A shoe comprising an upper, insole, outsole and heel, said upper having a vamp portion and opposite quarter portions, said vamp portion having a transverse toe edge and lower side edges that extend rearwardly from said toe edge and diverge laterally outwardly, said quarter portions having lower side edges extending rearwardly at an angle of the order of 135° from the rear end portions of the lower side edges of said vamp portion and converging laterally inwardly, the lower edges of said vamp and quarter portions thus defining a corner at their junction, said upper having a slit provided in each of the lower edges thereof a short distance forwardly of said corner, said slits extending inwardly from said edges, said outsole having forepart and shank portions, and said insole having forepart, shank and heel portions, the forepart of the insole throughout its width adhesively affixed directly to the forepart only of the outsole, the lateral edges of the forepart of the outsole projecting laterally outwardly beyond the lateral edges of the insole, said upper having its opposite lower edge portions from said toe edge to said slits turned outwardly and stitched to the projecting lateral edge portions of the outsole, the quarter portions of said upper rearwardly of said slits having lower edge portions lasted inwardly and adhesively secured between the shank portions of said insole and outsole, said shoe having its shank and quarter portions smoothly shaped to the shank of a selected last, and portions connecting the rear of one of said quarter portions with the rear of the other of said quarter portions.
